UNITED STATES PATENT OFFICE.

GEORGE E. DOUGHTY, OF NEW YORK, AND HERMAN FORTH, OF RIDGEWOOD, NEW YORK.

FILE, BINDER, AND THE LIKE.

Application filed January 5, 1927. Serial No. 159,073.

The present invention relates to letter files, temporary binders and the like of the type in which the ends of a binding tape or tongues are provided for receiving papers to be filed, and aims to provide certain improvements therein. In devices of this kind the binding tape or tongues which are flexible or bendable, are attached to one of the covers and are received in slots provided in a guard plate secured to the other cover, over which guard plate they are bent down, means being provided for holding the bent down portions of the tape ends or tongues in position against accidental displacement.

The object of the present invention is to simplify and improve the construction of the means for holding the tongues in position against displacement. This we accomplish by providing means in spaced relation to the tongue-receiving slots in the guard plate for holding the bent down tongues against accidental displacement. Preferably said means are formed integrally from the guard plate by slitting the same to provide resilient lips under which the bent down tongues are adapted to be received and held. The invention also includes other features of novelty which will be hereinafter more fully described.

A preferred embodiment of the invention is shown in the accompanying drawings, wherein

Figure 1 is a plan view of a file embodying our invention, a portion thereof being broken away.

Fig. 2 is a fractional view of Fig. 1 on an enlarged scale.

Fig. 3 is a section taken on line 3—3 of Fig. 2.

Fig. 4 is a section taken on the line 4—4 of Fig. 2.

Referring to the drawings, let A, A indicate the covers of a file or binder, B the back, and C and D the fillets or guards for supporting the binding elements of the file. As shown, the guards C and D are formed integrally with the covers and back by having portions of the material from which said parts are formed bent back upon itself in a manner well known in the construction of binder files. Supported by the guard C in any desirable manner are a pair of flexible tongues E adapted to receive and hold the papers F to be filed, the free end portions e of the tongues being receivable in

lateral slots in the guard D, after which they may be bent down over said guard to hold the papers against removal. To prevent undue wear on the guard D it is provided with a substantially U-shaped sheet 60 metal guard plate G having lateral slots g coinciding with the slots in the guard D, said slots being each formed with an in-cut or offset opening g', the purpose of which will presently appear. The guard plate G 65 is also preferably formed with the means for receiving the free ends e of the tongues after they are bent down over the guard plate to hold said tongues against accidental displacement. The file as thus far described 70 corresponds to the conventional type of files or temporary binders of the general class to which the present invention relates.

According to the present invention improved and simplified means are provided 75 on the guard plate for receiving and holding the bent down ends of the tongues against accidental displacement. These means preferably consist of a pair of resilient lips H disposed in spaced relation to 80 the tongue-receiving slots, said lips being integrally formed from the metal of the guard plate G and adapted to laterally receive the bent down tongue ends e.

The lips H are preferably formed by the 85 plate being slitted, as at h, through the bight of the U, said slits preferably extending through both faces of the plate, the top face of the plate being also slitted, as at h', between the slits h to provide the free end of 90 the lips. The top face of the lips H normally lie in the plane of the top face of the guard plate, and to facilitate the reception of the tongues beneath said lips the free end thereof are raised or bent up above the 95 plane of the guard plate, as best shown at h² in Fig. 3. Also, to further facilitate the entrance of the tongues under the lips, the free ends thereof are inclined in a direction 100 so as to progressively receive said tongues as they are laterally positioned beneath the lips. To render the lips H more resilient and afford them greater clamping power, they are provided with a struck-up rib h³ 105 extending longitudinally thereof.

In use the file or binder of the present invention is quite similar to those heretofore used in so far as the applying of the papers to be filed therein and the reception of the tongues upon which said papers are filed in 110

the lateral slots within the guard plate are concerned. Beyond this point the action of the present binder is believed to be more simple and efficient than those of previous constructions in that by a single operation the tongue can be bent down to lie flat against the guard plate and be moved laterally under the clamping lip to be held against accidental displacement. The incut portions 5 of the slots g in the guard plate facilitate this action and provide a smooth and neat bend in the tongue at said points. The integral structure of the tongue-holding means also results in a substantial saving of material and economy of time and labor in its production. As will be apparent, the metal guard plate is preferably stamped in the form of a flat blank at which time all incisions and slits may be made therein prior to 10 the bending of said plate to its U-shaped form.

While we have shown and described a preferred embodiment of our invention it will be understood that we do not wish to be limited to the precise structure disclosed, since 25 modifications thereof may be resorted to without departing from the spirit of the invention.

What we claim is:

30 1. A file or binder for sheets of paper and the like comprising a cover having opposite leaves and a flexible back connected to said cover leaves by fillets, a flexible tongue attached to one fillet and a guard plate attached to the other fillet and formed with an opening slot adapted to laterally receive said flexible tongue, said guard plate having a metallic lip in spaced relation to the opening slot, said lip being adapted to receive and 35 hold the tongue when it is bent down over said guard plate.

40 2. A file or binder for sheets of paper and the like comprising a member having a tongue upon which sheets of paper can be mounted, and a sheet metal member having 45

a slot adapted to laterally receive said tongue and permit it to be bent down to lie flat against said metal member, said metal member having an integral resilient lip formed by slitting and striking up a portion thereof 50 in spaced relation to the slot therein, said lip being adapted to laterally receive said tongue when it is bent down against said metal member and to hold said tongue against accidental displacement. 55

3. A file or binder of the type described comprising a sheet metal guard plate of U-shape in cross-section having a transverse slot therein extending through the bight of the U and an integral resilient lip in spaced 60 relation to said slot extending from the bight of the U toward the open end thereof, with the free end of the lip raised above the plane of the guard plate.

4. A file or binder of the type described 65 comprising a sheet metal guard plate of U-shape in cross-section having a transverse slot therein extending through the bight of the U and an integral resilient lip in spaced relation to said slot, said lip being provided by the plate being slitted through the bight 70 of the U, the free end of the lip raised above the plane of the guard plate.

5. A file or binder of the type described comprising a sheet metal guard plate of U- 75 shape in cross-section having a transverse slot therein extending through the bight of the U and an integral resilient lip in spaced relation to said slot, said lip being provided by the plate being slitted through the bight 80 of the U, the lip having its top face lying normally in the plane of the top face of the guard plate and having a struck-up rib extending longitudinally of the lip with the free end of the lip raised above the plane of 85 the guard plate.

In witness whereof, we have hereunto signed our names.

GEORGE E. DOUGHTY.
HERMAN FORTH.
